UNITED STATES PATENT OFFICE.

LUCIUS S. PRATT AND OLIVER A. WALLACE, OF WILMINGTON, NORTH CAROLINA.

FREIGHT-CAR DOOR.

Application filed March 31, 1923. Serial No. 629,148.

To all whom it may concern:

Be it known that we, LUCIUS S. PRATT and OLIVER A. WALLACE, citizens of the United States of America, and residents of Wilmington, North Carolina, have invented new and useful Improvements in Freight-Car Doors, which invention is fully set forth in the following specification.

This invention relates to freight-car doors, 10 and particularly to a car door which may be used either as a ventilating door, or as a closed door that will be proof against the elements.

It has heretofore been proposed to provide 15 a wooden ventilating freight-car door fitted with vertically disposed wooden slats that could be moved to open or closed position, as desired. This type of door is not only expensive to manufacture but is not durable 20 since after a short period of use the wooden slats become warped. Moreover, no means were provided for locking the slats in open or closed position. It is common practice, at present, to provide freight-cars with two 25 ventilated and two solid doors in order that the car may be properly ventilated. When ventilated doors are in place, or when not desired as ventilated car, the solid doors are used at door opening.

An object of this invention is to provide 30 a freight-car combination door, preferably formed entirely of metal, that may be used either as a ventilating door or as a closed door that will be proof against the elements 35 and pilfering, thereby effectively reducing the great cost incident to the use of two kinds of doors.

Another object of this invention is to provide 40 a rugged door of such construction that the same may be quickly and economically assembled. Further objects and novel features will appear hereinafter in the detail description of two forms of the inventive idea.

Generally speaking, the invention comprises 45 a car-door formed from a sheet of metal having one or more series of openings therein, said sheet of metal being reinforced or stiffened around its peripheral portion and, if desired, through its vertical central portion by a suitable stiffening means rigidly secured thereto. The openings formed in said plate are provided with ventilating slats mounted to be turned to open 50 or closed position on pintles, which pintles are secured in their proper position through

the medium of the stiffening means above referred to.

Referring to the drawings, wherein like reference numerals refer to like parts 60 throughout the several views,

Fig. 1 is a side elevation of one embodiment of the inventive idea, a portion of the same being broken away and certain parts removed in the interest of clearness, 65

Fig. 2 is an enlarged broken horizontal section on line 2—2, of Fig. 1,

Fig. 3 is a vertical sectional view through the door illustrating the slats in closed position, a portion of the same being broken 70 away,

Fig. 4 is a detail view similar to Fig. 3 illustrating the slats in open position,

Fig. 5 is a view similar to Fig. 4 illustrating one manner in which the slats of the 75 combination door may be formed,

Fig. 6 is a horizontal sectional view similar to Fig. 2 illustrating a second manner in which the improved door may be constructed, and, 80

Fig. 7 is a detail front elevation of one corner of the door constructed in accordance with the arrangement illustrated in Fig. 6.

Referring to Figs. 1 to 4, inclusive, 1 is a metal plate of any suitable thickness having formed therein a plurality of openings 2. While any number of openings may be provided in plate 1, the same are preferably arranged in two vertical series, each series comprising a plurality of aligned openings. 85 As clearly indicated in Figs. 3 and 4, openings 2 may be provided with flanges 3 which, instead of being normal to the surface of the plate are inclined at a small angle downwardly therefrom. In order to increase the 90 rigidity of plate 1 vertically extending ribs 4 and horizontally extending ribs 5 may be formed therein, and the periphery of said plate may be bent or pressed to form an outwardly extending flange 6. While plate 1 is preferably formed from a single metal sheet it will be apparent to one skilled in the art that the same may be made up of a plurality of sheets suitably fastened together. 95

Secured to the outer face of plate 1 in any suitable manner, as by means of bolts 7, is a stiffening or face plate 8 having a pair of openings 9 therein, each one of openings 9 being adapted to register with one series of openings in inner plate 1. Preferably face plate 8 is provided adjacent the lower edges of openings 9 with inwardly 100

projecting Z-portions 10, the inner ends of which engage plate 1. The upper edges of openings 9 are preferably formed as indicated in Fig. 3 with an inwardly extending portion engaging plate 1, and an outwardly bending portion in the form of an L-shaped flange 11. Face plate 8 is bent inwardly along the vertical sides of openings 9 in such a manner as to form inwardly extending flanges 12 which bear against the outer face of plate 1. Preferably the upper and lower edges of face plate 8 are provided with L-shaped flanges 13 which telescopically engage the outwardly turned flange 6 of plate 1. The vertically extending portions of said L-shaped flanges 13 provide tongues to engage guide ways (not shown) on the freight-car proper, along which the door is adapted to slide. In order to facilitate this movement of the door the same is provided with the usual or any desired type of hangers 14 and rollers 15 adjacent the upper edge thereof. If desired, a filler block 16 of any suitable material may be interposed between inner plate 1 and face plate 8 at the points where hangers 14 are secured to the door, to insure against buckling of the plates at these points.

Formed in the inwardly extending flanges 12 of face plate 8 are a plurality of pairs of notches or slots 17 for receiving pintles 18 of a plurality of slats 19, said pintles being secured to the opposite ends of said slats approximately midway of the end edges of the latter. Slats 19 are thus pivotally mounted in outer plate 8 adjacent each opening 2 in inner plate 1. Preferably the upper longitudinal edge of each of said slats is bent outwardly at an angle as indicated at 20 while the lower longitudinal edge of the slat is bent inwardly at an angle as indicated at 21 for a purpose to be hereinafter described. If desired, however, the upper longitudinal edge of each of said slats may be bent substantially at right angles as indicated at 22, Fig. 5.

Secured to face plate 8 centrally over the openings therein are brackets 23 having formed in the outwardly extending portions thereof a substantially vertical slot 24 which is adapted to receive a pin 25 secured to the upper end of a vertically disposed operating rod 26. Preferably rod 26 is a U or channel shaped bar having formed on the inner edges thereof pairs of ears 27 into the openings of which are fitted pins 28 that engage slots 29 formed at an angle to said rod in brackets 30 which are secured to the outer faces of slats 19. In vertical alignment with upper brackets 23 and slightly below the lower edge of openings 9 are a pair of brackets 31 having formed in the outwardly projecting portions thereof a pair of vertically aligned openings 32

which are adapted to register with a similar opening in rod 26. A hinge-pin 33 secured to rod 26 by means of a chain 34, may be employed for locking rod 26 in upper or lower position as desired. Any other suitable locking means may be provided for securing rod 26 in adjusted position.

It is particularly pointed out that the construction described hereinbefore is such as to greatly facilitate assembling of the parts. Outer plate 8 may be placed face downwardly and pintles 18, secured to slats 19, engaged in slots 17. Inner plate 1 may then readily be placed in position relative to outer plate 8 and the parts bolted together, the bolts 7 being so positioned that the nuts therefor are disposed in the strengthening ribs formed in plate 1 and do not project beyond the inner surface of the door. The various flanges and ribs in plates 1 and 8 may be pressed therein if desired.

When the combination door is to be used as a ventilating door it is only necessary to withdraw pin 33 and force rod 26 upwardly, the cam-action of slots 29 serving to tilt slats 19 about pintles 18 to the position shown in Fig. 4. When in full open position the inner ends of the slats bear against plate 1 while the outer ends rest against rod 26 thereby preventing rattling and wear of the parts. When slats 19 are moved to closed position as indicated in Fig. 3, the inwardly and outwardly bent ends of the same engage one with the other in such a manner as to form a perfectly closed door which will protect the contents of the car from the elements.

Another form of the inventive idea is shown in Figs. 6 and 7 wherein a flat inner plate 1', having formed therein a plurality of openings 2' arranged in a manner similar to that described above, is provided as the inner member of the door. Riveted to the periphery of plate 1' are Z-bars 35 having secured to the outer face thereof horizontally and vertically disposed plates 36 which form a structure corresponding to that of face plate 8. Secured to the inner face of plates 36 are L-shaped bars 37, the inner leg of the latter being in engagement with the outer face of plate 1' and having formed therein slots 17 to receive the pintles 18 of slats 19. Strips 38 are secured in any suitable manner to plate 1' in such a position as to engage the inwardly extending legs of the L-bars 37 and to serve as bearing members for pintles 18. The remainder of the construction is similar to that described in the preferred form of the invention.

We have thus provided a light, rigid door lending itself to ready assembly of the parts and which therefore may be constructed at a minimum cost for labor, and one which

may be used either as a closed or as a ventilating door as occasion may require, thereby doing away with a plurality of doors heretofore employed.

5 One form of the inventive idea lends itself readily to rapid manufacture, in plants where plate pressing facilities are available, while the other form lends itself with equal facility to construction in shops where means 10 for pressing plates are not available.

While two forms of the inventive idea have been specifically described herein and illustrated in the accompanying drawings it is to be distinctly understood the drawings 15 are for purposes of illustration only and are not designed as a definition of the limits of the invention, reference being had to the appended claims for this purpose.

What we claim is:—

20 1. A freight-car door comprising a plate having a plurality of openings therein, stiffening means secured to said plate, a plurality of slats pivoted in said stiffening means and means for turning said slats on their 25 pivots, and into engagement with said plate to uncover said openings.

2. A freight-car door comprising a plate having one or more series of openings therein, stiffening means secured to said plate, 30 a plurality of slats pivoted in said stiffening means, and means slidably secured to said stiffening means for moving said slats to cover and uncover said openings, adjacent slats being maintained at all times in overlapping relation.

3. A freight-car door comprising an inner plate having a series of openings therein, a stiffening plate secured to said inner plate having an opening therein in register with 40 said series of openings, a plurality of slats pivoted in said stiffening plate, and means engaging said slats to turn them on their pivots.

4. A freight-car door comprising an inner plate having a series of openings therein, a stiffening plate secured to said inner plate having an opening therein in register with said series of openings, a plurality of slats having their upper edges bent outwardly and 50 their lower edges bent inwardly pivoted in said stiffening plate, and means engaging said slats to turn them on their pivots to cover or uncover said series of openings.

5. A metal freight-car door comprising an inner plate having one or more series of openings therein, a stiffening plate having one or more openings therein secured to said

inner plate, each opening in said stiffening plate being in register with a series of openings in said inner plate, a plurality of slats pivoted in said stiffening plate, and means for turning said slats on their pivots to cover or uncover the opening in said inner plate, the movement of said slats to uncover said openings being limited by engagement 65 of the slats with said means.

6. A metal-freight car door comprising an inner plate having a series of openings therein, a stiffening plate having an opening therein in register with said series of openings secured to said inner plate, a plurality of slats pivoted in said stiffening plate, a plurality of brackets having slots therein secured to said slats, and means engaging 70 said brackets for turning said slats on their 75 pivots.

7. A freight-car door comprising an inner metal plate having a plurality of flanged openings therein and an outwardly projecting flange around the periphery thereof, an outer stiffening plate secured to said inner plate having openings therein, and an inwardly extending flange adapted to telescopically engage the flange of said inner plate, a plurality of slats pivotally secured 80 to said outer plate, the upper edges of said slats being bent outwardly and the lower edges of the same being bent inwardly, and means for moving said slats to cover said openings, the upper edge of each intermediate 85 slat being adapted to engage the lower edge of the next adjacent slat when the same are moved to covering position.

8. A freight-car door comprising, in combination, a plate having one or more openings therein, stiffening means secured to said plate, a plurality of overlapping slats secured to said stiffening means for closing said openings, and means for moving said slats to uncover said openings and for preventing movement of the same to non-lapping position.

9. A freight-car door comprising a plate having a plurality of openings therein, stiffening means secured to said plate, a plurality of slats pivoted in said stiffening means with one edge portion of each slat engaging said plate when in open position, and means for turning said slats on their pivots.

In testimony whereof we have signed this specification.

LUCIUS S. PRATT.
OLIVER A. WALLACE.
